SASH LOCK

Isidore Birman, Peekskill, N. Y.

Application June 11, 1938, Serial No. 213,170

2 Claims. (Cl. 70—90)

The object of the present invention is to provide a sash lock constituting an improvement over such devices of the same general type as shown in the patent to Lindgren, No. 1,704,946 of March 12, 1929, in that the device provides a safer locking construction and, at the same time, has greater simplicity of construction and is of low cost.

The invention will be described with reference to the accompanying drawing, in which:

Figure 1 is a view in elevation of a pair of window sash members to which an embodiment of the invention has been applied, the sash members being shown in partly open position for ventitating purposes.

Figure 2 is an enlarged fragmentary section elevation on the line 2—2, Figure 1.

Figure 3 is an enlarged fragmentary sectional elevation on the line 3—3, Figure 1.

Figure 4 is an elevation of the face plate employed in the modified device shown in Figure 4A.

Figure 4A is a view in transverse section of a horizontal window frame member showing, partly in section, the cam latch portion of a modification of the structure illustrated in Figures 1 and 2.

Figure 5 is a side elevation of the device shown in Figure 4, partly in section.

Figure 6 is a plan view of the complete device, certain elements being shown in dotted lines.

It has been recognized that the usual rotary cam latch applied to sash windows at the central portion of the same gives insufficient locking protection for windows inasmuch as the removal of a section of the glass forwardly of the latch enables ready release of the latch by normal rotation. Also, the rotary cam latching member moves on a pivot and hence a single headed stud must be used as a pivot member, making it easy for a marauder to wrench the latch from its pivot by a leverage force applied through a metal bar.

By means of the present invention, unlike existing devices of the type, the window sash will be locked even after forcible removal of the rotary cam latch, although the latter is employed to throw into action the supplemental locking means by which said effect is produced. Forcible removal of the rotary cam latching member will not expose the connection between the same and the supplemental lock actuating means, the latter still being held guarded and in a dead center position relatively to the pivot member for the rotary latch, so that the supplemental locking member is latched.

Referring to the drawing, the rectangular line indicated at 1 indicates a window frame in which are slidably mounted a lower sash member 2 and an upper sash member 3. As customary, the upper sash member has fastened thereto a receiving catch 4 for the rotary cam latch member 5.

The rotary latch member 5 is apertured to receive a headed stud 6 which carries a disk 7 having an eccentrically disposed pin 8. The rotary latch member 5 is disposed above a base plate 9 secured to the lower sash 2 not only by a plurality of vertically extending screws 10, but by a relatively heavy screw 11, which screw 11 passes entirely through the sash 2, first entering a depending flange 9x of the plate 9 and finally passing through a second depending flange 9xx of said plate. The disk 7 rotates with rotary latch member 5, being disposed within a recess formed in the bottom wall of plate 9.

Connected to pin 8 is one end of a rod 12 having a cam face at 13. The cam face end of rod 12 enters a transversely extending guide channel indicated at 14, Figures 6, and formed in a casing 15, the casing having a longitudinally extending chamber in which is disposed a locking pin 16 formed at its inner end with an enlarged head 16x which engages the cam face of rod 12. A spring fixed at one end and bearing upon the enlarged head 16x normally moves the pin inwardly and thus out of operative position. The pin is thrown into operative position by movement of rod 12 to the position shown in Figure 6. It will be noted that when the rod is in such locking position, pin 8 is disposed at 35 a dead center position relatively to headed stud 6. Thus, it is impossible to move rod 12 to release locking pin 16 unless disk 7 is rotated. The effect of this construction is that should the rotary latch member 5 be forced upwardly and 40 turned away from headed stud 6, it still will be impossible to release the supplemental lock.

To hold rotary latch member 5 in latching position, I provide on rotary latch member 5 a casing 5x formed with a horizontal lock barrel receiving aperture in which is disposed the key-operated barrel 17 adapted to receive the key 18. The construction of the key-operated barrel forms no part of the present invention and therefore is only schematically shown.

Rotation of the barrel will throw downwardly a locking pin 19 and the pin will enter a hole formed in base plate 9, as shown more particularly in Figure 5. The latter operation will lock the rotary latch member. This locking is effect-

ed after the said latch member 5 is moved to a position where rod 12, through its cam end 13, will have operated locking pin 16 to enter one of a plurality of holes formed in a plate 20 carried by the upper sash 3.

In Figure 4 the base plate 9 at its front edge is formed with a channel to receive the horizontal flange of a movable plate 9a. At the exterior of the plate is a washer 11b having a reduced extension which enters an aperture in plate 9a, the washer being provided with a threaded aperture to receive screw 11a. From the rear edge of plate 9 extends an integral depending flange 9b through which the head-end of screw 11a passes. This arrangement enables the application of the device to upper frame members 2 of various thicknesses.

Having described my invention, what I claim and desire to secure by Letters Patent, is as follows:

1. A sash lock comprising a base plate having means for securing the same to the upper horizontal sash frame member of the lowermost of two vertically slideable sash members, the base plate being formed at its underface with a chamber, a rotary disk disposed in said chamber and carrying an axially positioned stud projected up-

wardly through the base plate, a pivot pin eccentrically depending from the disk and adapted to receive one end of a bar for operating supplementary sash locking means, a rotary cam latch mounted on the upper end of said stud and adapted to engage receiving catch means carried by the upper sash, and key-operable lock means carried by said cam latch and including a bolt adapted to be projected downwardly from the cam latch into an aperture formed in said base plate.

2. A sash lock constructed in accordance with claim 1, in combination with a supplementary bolt operating bar having one end thereof mounted upon said eccentrically depending stud of the rotary disk, said stud, the cam latch and the vertically extending axial stud carried by the rotary disk being so related that when the cam latch is rotated to operative position the depending stud is moved to dead center position relative to the axis of movement of the rotary cam latch, whereby removal of the cam latch from the upwardly projecting stud of the rotary disk will be ineffective to permit rotation of said disk by a longitudinal movement of the rod.

ISIDORE BIRMAN.
